(57) **CLAIM**

The ornamental design for an inhaler sleeve with spring clip,
as shown and described.

DESCRIPTION

FIG. 1 is a right side elevation view of an inhaler sleeve with
spring clip showing my new design;

FIG. 2 is a left side elevation view thereof;

FIG. 3 is a front elevation thereof;

FIG. 4 is a rear elevation thereof;

FIG. 5 is a top plan view thereof; and,

FIG. 6 is a bottom plan view thereof.

The broken line showing in FIGS. 1 through 5 of the
medication container are for illustrative purposes only and
forms no part of the claimed design.
